UNITED STATES PATENT OFFICE.

BYERS W. KADEL, OF ROANOKE COUNTY, VIRGINIA.

RAILWAY-CAR.

1,263,427.

Specification of Letters Patent. Patented Apr. 23, 1918.

Application filed April 4, 1917. Serial No. 159,671.

To all whom it may concern:

Be it known that I, BYERS W. KADEL, a citizen of the United States, residing in the county of Roanoke and State of Virginia, have invented certain new and useful Improvements in Railway-Cars, of which the following is a specification.

This invention relates to railway cars and the principal object thereof is to provide an improved form of body bolster and improvements in the related car construction. The invention consists of the formation, combination and arrangement of parts as will be herein set forth and finally pointed out in the appended claims.

In the drawings, Figure 1 is a partial transverse vertical section through a car body showing in side elevational view an embodiment of the body bolster of my construction and its relation to the adjacent parts of the car body. Fig. 2 is a fragmentary plan view of the same showing the body bolster in plan view. Fig. 3 is an inverted plan view showing the bottom construction of the same. Fig. 4 is a transverse vertical section through the bolster taken on the line 4—4, Fig. 1, and Fig. 5 is a similar view taken on the line 5—5 of Fig. 1.

Referring now to these drawings, the car is supplied with sides, one of which is indicated at 1, the other being broken away, and a floor 2. For draft purposes there is provided a flanged center sill 3, extending longitudinally of the car, this in the present instance being formed of two channels with vertical webs and top and bottom flanges. In the drawings but one of the channels 4 is shown, the other being broken away, the center sill being disposed centrally of the car. This construction, however, is well known in the art and will be readily understood. A top cover plate 5 is riveted to the top flanges of the channels and securely boxes and ties together the channels, this cover plate serving also as a part of the car floor.

To the inside of the car side is riveted a vertical angle 6 and to the lower edge of the car side may be secured a reinforcing member such as the bar 7.

The body bolster extends transversely of the car from car side to car side and embodies a web 8 which is attached to the in-turned leg of the angle 6. There is also secured to the car side an angular casting 9 having an inwardly-turned leg and this leg is

disposed at a sufficient distance from the leg of the angle 6 to admit the web plate 8 between them. The rivets such as 10 then pass through all three members and make a secure fastening for the bolster web. The casting 9 is formed to underlie the lower end of the angle 6 and may also underlie the car side 1 and reinforcement 7 and is there flattened out to form a jacking surface 11.

The bolster is provided with upper flange angles 12 which are secured to the opposite sides of the web 8 and with their outstanding flanges at the top. These angles are reinforced at intervals as they approach the center of the car where the strains are greater by the top cover plates 13 and 14 and over the center sill additional angles 15 are applied to the angles 12 and to the web 8 to further reinforce the top bolster flange at this point of greatest strain. These angles are applied with their outstanding legs down and these transfer a portion of the vertical forces in the bolster directly to the center sills against which they bear, the floor plates 2 and cover plate 5, which are located in adjacent planes, being interposed.

To transfer other portions of the vertical load of the bolster to the center sills, angles 16 are secured to the opposite sides of the web 8 and their outstanding legs are disposed against and secured to the webs of the center sill channels.

The floor plates 2 are affixed to the side of the car by means of suitable angles 17 and to the bolster web by means of angles 18. The floor is also secured to the outstanding legs of the upper flange angles 15.

Thus the upper flange of the bolster passes uninterruptedly over the center sills and is disposed wholly above the floor of the car and within the car body. Not only is splicing of the upper flange avoided but a bolster of greater strength and depth is provided.

Lower flanges for the bolster are formed by securing to the opposite sides of the web and along its lower edge the angles 19. These are disposed beneath the car floor and with their outstanding flanges down and one or both of them may extend out and be secured to the outstanding legs of the angle 6 and the casting 9. At the center these angles are cut away to permit the uninterrupted passage of the center sill and a bottom splice plate 20 is secured to the horizontal outstanding flanges of these angles, this plate extending beneath the center sill and out-

ward toward the opposite sides of the car so as to complete the continuity of the bottom bolster flange.

It is usually expedient because of limitations of space or for other reasons to incline the bottom flanges of the bolster, thus making the bolster deeper at the center than at its ends. The plate 20 is formed or bent to follow this angularity of the flange angles 19.

10 Beneath the center sill and beneath the plate 20 is secured the body center plate 21, securing rivets passing through this center plate, through the splice plate 20 and 15 through the bottom flanges of the center sill and tying them all together. Thus in effect the cut ends of the angles 19 are affixed to the center sill through the medium of the center plate rivets.

20 The force from the angles 19 being transferred to the angular portions of the plate 20 sets up a bending stress at the angle of this plate and tends to distort it. To reinforce the plate 20 against this action, and 25 to further tie together the cut ends of the angles 19, the center plate 21 is provided with angular extensions or flanges 23, which overlie the cut ends of the angles 19 and are shaped to fit over the bend in the plate 20. 30 When the several parts are then riveted together it will be seen that the center plate, which is of cast steel, will materially assist the plate 20 in resisting these deforming forces, at the same time tying the angles 19 35 together.

A bolster center casting or center sill filler 22 is secured between the channels 4 immediately over the center plate 21 to assist in supporting it.

40 Thus I have produced a body bolster and car construction of great strength and of economical design, and while for some classes of lading the fact that the plane of the floor intersects the plane of the bolster web would be a disadvantage, yet for such 45 service as modern coal-carrying cars where the cars are handled in a dumping machine the presence of the upper portion of the bolster within the cavity of the car is not 50 objectionable.

Having thus described the present embodiment of my invention, I claim:

1. In a railway car having sides and a floor, a body bolster having a web and top 55 and bottom flanges and extending across the car from one side thereof to the other, the plane of the said floor intersecting the plane of the bolster web and the said floor being affixed to the said web.

60 2. In a railway car having sides and a floor, a body bolster extending transversely of the car from one car side thereof to the other, said body bolster having upper and lower flanges, the upper flange being dis- 65 posed wholly above the car floor and the

lower flange being disposed beneath the car floor.

3. In a railway car having sides and a floor, a body bolster having top and bottom flanges and a connecting web and extending 70 across the car from one side thereof to the other, the upper flange being disposed above the car floor and within the car body and the lower flange being disposed beneath the car floor, the said floor being affixed to the 75 said bolster web.

4. In a railway car having sides and a floor and having a centrally disposed, longitudinal center sill, a body bolster having upper and lower flanges and a connecting 80 web and extending across the car from side to side, the plane of the said floor intersecting the plane of the bolster web and being attached to the said web, the said floor being in substantially the same plane as the 85 top surface of the center sill and being attached thereto.

5. In a railway car having sides and a floor and having a centrally disposed, longitudinal center sill, a body bolster having 90 upper and lower flanges and a connecting web and extending across the car from one car side to the other, the said upper flange extending uninterruptedly over the said center sill and above the car floor and the 95 lower flange being intercepted by the said center sill, there being means passing beneath the said center sill for joining together the intercepted ends of the said bottom flange, the said floor being attached to 100 the upper portion of the center sill.

6. In a railway car having sides and a floor and having a centrally disposed, longitudinal center sill, a body bolster having upper and lower flanges and a connecting 105 web and extending across the car from one car side to the other, the said upper flange extending uninterruptedly over the said center sill and above the car floor and the lower flange being intercepted by the said center 110 sill, there being means passing beneath the said center sill for joining together the intercepted ends of the said bottom flange, the said floor being attached to the upper portion of the center sill and to the web of the body 115 bolster.

7. In a railway car having sides and a floor and having a centrally disposed, longitudinal center sill, a body bolster having upper and lower flanges and a connecting 120 web and extending across the car from one side to the other, the upper flange thereof passing uninterruptedly over the said center sill and the lower flange thereof being affixed to the center sill, and means separable 125 from but forming a part of the said upper flange for delivering a portion of the vertical load in the bolster to the said center sill, the car floor being attached to the said center sill and to the said load-delivering means. 130

8. In a railway car having sides and a floor and having a centrally disposed, longitudinal center sill, a body bolster having upper and lower flanges and a connecting web and extending across the car from one side to the other, the upper flange thereof passing uninterruptedly over the said center sill and the lower flange thereof being affixed to the center sill, and means separable from but forming a part of the said upper flange for delivering a portion of the vertical load in the bolster to the said center sill and there being additional means attached to the web of the said bolster for delivering another portion of the said vertical load to the said center sill.

9. In a railway car having sides and a floor and having a centrally disposed, longitudinal center sill, a body bolster having upper and lower flanges and a connecting web plate and extending across the car from one side to the other, the upper bolster flange embodying a pair of angles having their vertical legs secured to the opposite sides of the said web plate and their horizontal legs outstanding from the upper edge of the same, the said flange angles passing continuously and uninterruptedly over the said center sill, the said car floor being secured to the upper edges of the said center sill and to the web plate of the body bolster and below the said flange angles, there being additional angles having their vertical legs secured to the said bolster above the car floor and their horizontal legs supporting the car floor and supported upon the said center sill.

10. In a railway car, a central, longitudinally-disposed center sill, a bolster extending transversely of the car and having top and bottom flanges and a connecting web, 40 the web and the said bottom flange being cut away to admit the said center sill and the said bottom flange being inclined upwardly from the lower edges of the center sill toward each side of the car, and a center plate 45 affixed to the center sill, said center plate having extensions which overlie and are secured to and formed to fit the contour of and to brace the adjacent inclined ends of the intercepted bottom bolster flange at each 50 side of the center sill.

11. In a railway car, a central, longitudinally-disposed center sill, a bolster extending transversely of the car and having top and bottom flanges and a connecting web, 55 the web and the said bottom flange being cut away to admit the said center sill and the said bottom flange being inclined upwardly from the lower edges of the center sill toward each side of the car, a tie plate 60 extending beneath the said center sill and fitted to and joining together the adjacent ends of the intercepted bottom bolster flange, and a center plate affixed to the center sill and the tie plate, the said center plate having 65 extensions which overlie and are secured to and formed to fit the contour of and to brace the inclined bottom bolster flange at each side of the center sill.

In testimony whereof I affix my signature. 70
